CHAIN OR LINKAGE

Charles H. Kestenman, Providence, R. I., assignor
to Kestenman Bros. Mfg. Co., Providence, R. I.,
a corporation of Rhode Island

Application April 6, 1938, Serial No. 200,397

10 Claims. (Cl. 59—80)

The present invention relates to articles of jewelry and particularly to improvements in flexible chains or linkages having hollow box-type links.

One of the objects of the present invention is to provide an article of the type indicated which may be constructed of relatively light stock while being strong and durable in use.

Another object of the invention is to provide an article of the type indicated having hollow links of improved construction for mounting gems or other ornaments.

Another object of the invention is to provide hollow box-links of the type indicated having a minimum number of parts adapted to be conveniently constructed from sheet-metal stampings.

Further objects of the improvement are set forth in the following specification which describes, by way of example, a preferred form of jewelry chain or linkage as illustrated by the accompanying drawing. In the drawing:

Fig. 1 is a plan view of a linkage embodying a series of the present improved box-links joined by looped connecting links to form a bracelet chain;

Fig. 2 is an enlarged plan view of a portion of the chain shown in Fig. 1 with one of the box-links illustrated partly in section to show the hollow construction of the body-member and the frame for supporting a gem therein;

Fig. 3 is a side elevational view of a portion of the chain with one of the box-links illustrated in section to show the connecting loops at its ends engaging shoulders on the gem-supporting frame to hold the latter in position in the body-member;

Fig. 4 is a transverse sectional view taken on line 4—4 of Fig. 2 showing the gem supported by the frame and the frame supported by the inturned side walls of the link; and

Fig. 5 is a perspective view of the parts of one of the hollow box-links shown in disassembled relationship.

It is desirable in the jewelry art that the links of chains and bracelets be designed to give the appearance of weight and solidity, while at the same time being of light skeleton construction to save stock; especially when the links are made of precious metals. For this reason prevailing styles of bracelets and chains are constructed, at least in part, from hollow links and the present invention provides a hollow box-type

link of novel construction with means for setting a gem in an opening in its top wall.

Referring now to the drawing, the jewelry chain or linkage herein illustrated is composed of ornamented box-links 1 incorporating the novel features of the present invention, alternating with looped connecting links 2. Each box-link 1 comprises a body-member 3 of sheet-metal blanked out and formed to provide a crowned top 4, depending side walls 5, and end flanges 6 folded to form opposite connecting loops. The top wall 4 has an opening 10 of any suitable contour to expose an ornament 11 mounted or set in the body-member 3. Although the ornament 11 is herein illustrated in the form of a gem or jewel, it will be understood that it may take other forms. The gem or other ornament 11 is supported in the body-member 3 by means of an inverted tray-like frame 12 blanked from sheet-metal and folded to provide a bottom wall 13 and upstanding side and end flanges 14 and 15. The arrangement is preferably such that the ends of the end flanges 15 of the frame 12 abut the inside face of the top wall 4 of the body-member 3 adjacent the sides of the opening 10, while the side flanges 14 engage the gem or other ornament 11 adjacent its edges to hold it in engagement with the edges of the opening 10 in the top wall.

The frame 12 is held in position in the body-member 3 by inwardly-folded terminal portions 7 at the bottom of the side walls 5 and the ends of the looped flanges 6, these several parts engaging the bottom wall of the frame on four sides. Preferably the bottom wall 13 of the frame 12 is struck up or embossed to provide pairs of opposite shoulders 17 and 18 which abut and interlock with the ends of the bent portions 7 of the side walls 5 and the ends of the looped flanges 6 to positively hold the frame in position in the body-member. As illustrated most clearly in Figs. 4 and 5, the bottom wall 13 has an embossed table 16 of rectangular outline to form the pairs of opposite shoulders 17 and 18. The shoulders 17 and 18 are of a depth equal to the thickness of the end portions 7 and flanges 6 so that when the latter are interlocked with the shoulders they form a continuation of the bottom face of the table 16 to provide a smooth finish for the bottom of the link 1.

It has been stated that the frame 12 is held from longitudinal movement in the body-member 3 by the engagement of the ends of the looped flanges 6, but it is also to be noted that

the frame is prevented from such movement by the peculiar formation of the top wall of the body-member where the flanges are bent downwardly or inclined towards the bottom of the link. That is to say, even when the ends of the flanges 6 are bent downwardly away from the bottom of the frame 12 the frame will still be held from longitudinal movement in the body-member by the inclined bent portions of the flanges, as indicated most clearly in Fig. 3 of the drawing. This particular feature of construction provides that when the loops at the end of the link are opened to increase or reduce the length of the chain or bracelet, for example in fitting the bracelet to the wrist of the wearer, the frame 12 will not be loosened in the body-member to shift its position longitudinally thereof.

The connecting links 2 may be of any desired configuration, being preferably formed of sheet-metal stock and generally curved or bowed to conform to the contour of the wrist of the wearer of the bracelet. Each of the links 2 has a central opening 20 to form a loop with side bars 21 and connecting webs 22 at its ends. The links 2 are pivotally connected to the ends of a pair of the box-links 1, the opposite bars 22 of each link 2 passing through the adjacent looped flanges 6 on the box-links. The connecting links 30 2 thus pivotally connect the series of box-links 1 to provide an articulated chain or linkage.

The individual links of the chain or linkage are assembled by a preferred method which consists in first inverting the body-member 3 of a box-link 1 so that the end flanges 6 and side walls 5 project upwardly as illustrated in Fig. 5, prior to their being folded inwardly. The gem or other ornament 11 is placed in the opening 10 so that it is engaged adjacent its edges by the edges of the top wall 4 surrounding the opening 10 and a pair of connecting links 2 are looped around the upstanding flanges 6. The frame 12 is placed in the body-member 3 to engage its side flanges 14 with the gem or other ornament 11 adjacent the edges of the latter as illustrated in Fig. 4. The end portions 7 of the side walls 5 and the end flanges 6 are then folded inwardly into engagement with the pairs of opposite shoulders 17 and 18 on the bottom of the frame 12 to retain the latter in position in the body-member 3. The folding of the end flanges 6 forms closed loops which embrace the bars 22 of the connecting links 2 to pivotally connect the latter to the box-link 1. The interlocking engagement of the end portions 7 of the side walls 5 and the ends of the flanges 6 with the shoulders 17 and 18 on the bottom of the frame 12 holds the frame against movement either laterally or longitudinally of the hollow link 1. It will also be observed that the end portions 7 and flanges 6 form a continuation of the bottom wall of the table 16, giving the hollow box-link 1 a solid finished appearance. It will be understood that the box-links 1 and connecting links 2 are successively added until a chain or linkage of suitable length has been formed and that the operation of bending the end portions 7 of the side walls 5 and the end flanges 6 is preferably performed in a suitable machine fixture although it may be performed manually.

It will be observed from the foregoing that the present invention provides a chain or linkage having box-links of improved construction for mounting gems or other ornaments. It is to be understood, however, that the invention may be

embodied in a chain or bracelet having box-links without the gem or jewel setting and ornamented in other ways as for example, by embossing, engraving, enameling or any other method such as well known in the jewelry art. It will also be observed that the box-type links are of simple construction having a minimum number of parts and requiring a minimum number of operations to assemble them together to form a chain or linkage.

While the invention is herein shown as embodied in a preferred form of chain or linkage construction, it is to be understood that various modifications may be made in the structure and arrangement of the parts of the linkage without departing from the spirit or scope of the invention. Therefore, without limiting myself in this respect, I claim:

1. A hollow link for bracelets, chains and the like comprising a body-member having a top wall, depending sides, and extensions of its top wall bent around to form loops; and an inner member of tray-like construction having a bottom and side walls, said tray-like member being enclosed between the sides of the body-member with the ends of its sides abutting the under side of the top wall thereof and with the ends of the loops of the body-member engaging against the bottom wall of said inner member.

2. A hollow link for bracelets, chains and the like comprising a body-member having a top wall with sides depending therefrom, and extensions from its top wall bent around to form loops at its ends; and an inner member having a bottom and upwardly-projecting side walls, said inner member being retained in position within the body-member by portions of the side walls thereof folded across its under side and by the ends of the loops bearing against its under side.

3. A hollow link for bracelets, chains and the like comprising a body-member constructed of sheet-metal with a top wall, sides depending therefrom, and extensions of its top wall bent around to form loops at its ends; an inner sheet-metal member having a bottom wall with sides projecting upwardly therefrom, said bottom wall being embossed to provide pairs of opposite shoulders, said inner member being held within the body-member by folded portions of the sides thereof overlying its edges in abutting relation to certain of the shoulders thereon and with the ends of the loops engaging the bottom of said inner member in abutting relation to other of the shoulders.

4. A hollow link for bracelets, chains and the like comprising a body-member having a top wall formed with an opening therein, sides depending from the top wall and terminating in portions folded inwardly therefrom, extensions of the top wall bent around to form loops at the ends of the body-member; an ornament projecting upwardly through the opening in the body-member; and an inner member having a bottom wall with sides projecting upwardly therefrom, the edges of the sides of the bottom member engaging the ornament to position it in the opening in the top wall of the body-member, said inner member being retained within the body-member by the folded bottom portions of the sides thereof and the ends of the loops abutting against the bottom wall of said inner member.

5. A hollow link for bracelets, chains and the like comprising a body-member having a top wall with an opening therein and depending side walls with inturned bottom portions, the end

portions of the top wall being folded to provide loops, a gem in the opening in the top wall, a frame for supporting the gem in the opening in the top wall, and means on the frame interlocking with the inturned portions of the depending side walls of the body-member and the ends of the loops to hold the frame rigidly within the body-member.

6. In an ornamental chain or bracelet, a series 10 of hollow links, each link comprising a body-member having a top wall with an opening therein, an ornament exposed in said opening in the top wall, a frame for supporting the ornament in the opening, loops on the body-member connecting its top wall with the frame, and links connecting the loops of adjacent hollow links.

7. In an ornamental chain or bracelet, a series 20 of hollow links, each link comprising a body-member having a top wall with an opening therein, in and depending side walls, an ornament exposed in said opening in the top wall, a frame within the body-member for supporting the ornament, the end portions of the top wall being formed into loops having their ends engaging the 25 frame to hold it in position in the body-member, and links connecting the loops of adjacent hollow links.

8. In an ornamental chain, a series of hollow 30 links, each hollow link comprising a body-member having a top wall with an opening therein and depending side walls with inturned ends, the end portions of the top wall bent around to form loops, a gem in said opening engaged by the edges of the top wall surrounding the opening, 35 a hollow frame within the body-member having flanges engaging the gem to hold it in engagement with the top wall, said frame being held in

position in the body-member by the engagement therewith of the inturned bottom portions of the side walls and the ends of the loops, and links connecting the loops of adjacent hollow links.

9. In an ornamental chain, a series of hollow 5 links, each hollow link comprising a body-member having a top wall with an opening therein and depending side walls with inturned bottom portions, the end portions of the top wall being bent to form loops, a gem in said opening engaged by 10 the edges of the top wall surrounding the opening, a hollow frame in the body-member having flanges engaging the gem to hold it in engagement with the top wall, said frame having shoulders on its bottom engaged by the inturned portions 15 of the side walls and the end of the loops to hold the frame in position in the body-member, and links connecting the loops of adjacent hollow links.

10. A hollow link for bracelets, chains and the 20 like comprising a body-member having a top wall with sides depending therefrom and extensions of its top wall inclined downwardly therefrom at a relatively sharp angle to provide shoulders, said extensions being bent around to 25 form loops at the end of the body-member; and an inner member having a bottom and upwardly-projecting side and end walls, said inner member being retained in position within the body-member by portions of the side walls thereof folded 30 across its under side and by the shoulders between the top wall and its inclined extensions abutting the edges of the end walls of the inner member to hold it against longitudinal movement in the body-member.
